AUTOMATIC REFRIGERANT STORAGE FOR REVERSIBLE HEAT PUMP

William S. McKinney, Huntington Beach, Calif., assignor
to The Coleman Company, Inc., Wichita, Kans., a cor-
poration of Kansas
Filed Nov. 5, 1965, Ser. No. 506,553
6 Claims. (Cl. 62—149)

This invention relates to an automatic refrigerant stor-
age for a reversible heat pump, and more specifically,
to a reversible heat pump with improved means for ad-
justing the effective charge of refrigerant.

It has been previously observed, in Hopkins Patent
2,589,384, that in any commercially useful reversible heat
pump, the refrigerant charge which is correct for one
direction of flow is wrong for the other direction. Hop-
kins, therefore, teaches the interposition of a refrigerant
storage tank in the circuit of the heat pump, such tank
being disposed adjacent the heat exchanger which oper-
ates as a condenser when the larger charge is needed, and
being connected by a tube with a part of the circuit
which is at the pressure of the other heat exchanger.

In practice, it has been found that such a storage tank
provides, at best, only a partial solution to the problem.
While the storage tank does have the effect of automatically
adjusting the charge, it also produces, or cooperates
with the other components of the system to produce,
certain undesirable side effects. For example, in a heat
pump which requires a larger charge during the cool-
ing cycle, a change-over from heating to cooling will
cause refrigerant to surge from the storage tank located
adjacent the outdoor coil (which acts as a condenser
during the cooling cycle) and into the system. Rapid
emptying of the storage tank may cause flooding of the
evaporator coil and, if liquid refrigerant then continues
on the compressor, the oil of the compressor will be di-
luted and the slug of liquid refrigerant entering the com-
pressor may even damage the valves.

Ordinarily, heat pump systems require a greater charge
during the cooling cycle. The storage tank thus removes
excess charge on the heating cycle to give optimum ca-
pacity to the heatpump; however, such optimum capaci-
ties are usually based on conditions which will exist
during mild outdoor temperatures. As outdoor tem-
peratures fall below this predetermined level, the out-
door coil, which acts as an evaporator during the heating
cycle, receives less and less heat from the air and, if a suf-
ficiently low outdoor temperature is reached, liquid re-
frigerant will be drawn into the compressor, again re-
ducing the viscosity of the oil to a point which may cause
compressor breakdown.

Accordingly, it is an object of the present invention
to provide a reversible heat pump in which the charge
is automatically adjusted to suit the particular cycle of
operation, without the dangers and disadvantages de-
scribed above. Specifically, it is an object to provide a
heat pump equipped not only with a storage tank for
withdrawing excess refrigerant from the system during
certain conditions of operation, but also with additional
storage means which coacts with the tank for automatic-
ally controlling the charge and for eliminating or reduc-
ing those operating conditions which might otherwise re-
sult in compressor breakdown.

Other objects will appear from the specification and
drawings in which:

FIGURE 1 is a generally diagrammatic view of a heat
pump circuit illustrating the direction of refrigerant flow
when the heat pump is in its cooling cycle of operation.

FIGURE 2 is a diagrammatic view similar to FIGURE
1 and showing the heat pump during its cooling cycle, but

under conditions where there is a high internal load on
the system.

FIGURE 3 is a diagrammatic view similar to FIGURE
1 but illustrating the operation of the system when the
heat pump is in its heating cycle of operation.

FIGURE 4 is similar to FIGURE 3, showing the heat
pump during its heating cycle of operation, but under
conditions where the outside temperature is extremely low.

As previously indicated, it is a characteristic of re-
versible heat pumps that a refrigerant charge which is
correct for one direction of operation is wrong for the
other direction. Normally, a larger charge is needed
during the cooling cycle and, therefore, excess charge
must be removed during the heating cycle. The accom-
panying drawings refer to such a system; that is, a sys-
tem in which excess charge must be removed during the
heating cycle, and must be returned to the system during
the cooling cycle, in order to maintain optimum operating
conditions. It will be understood as the specification
proceeds, however, that the teachings of the present in-
vention are also applicable to a heat pump in which the
larger charge is required during the heating cycle and
the smaller one during the cooling cycle.

The heat pump diagrammatically illustrated in FIG-
URE 1 comprises two coil heat exchangers 10 and 11,
a motor-driven compressor 12, a 4-way reversing valve
13, and a capillary tube arrangement 14, which operates
as a long-path restrictor.

Between reversing valve 13 and compressor 12 is a
suction line 15 through which refrigerant vapor is con-
veyed to the compressor. A discharge line 16 extends
from the compressor back to the reversing valve and
carries refrigerant under pressure to the valve and to the
particular coil 10 or 11 which has been selected to op-
erate as the condenser.

The capillary tube arrangement 14 includes capillary
tubes 17 and 18, the former being operative during the
heating cycle and the latter being operative during the
cooling cycle. Lines 19 and 20, each equipped with a
check valve 21 and 22, direct the flow of refrigerant to
the capillary tubes. During a cooling cycle, when the
refrigerant flows in the direction indicated by arrows
23, line 19 is operative to convey refrigerant from the out-
door coil 10, which operates as a condenser, to capillary
tube 18. The flow of refrigerant from line 19 through
line 20 is blocked by check valve 22. On the other hand,
when the flow of refrigerant is reversed during the cool-
ing cycle, as indicated by arrows 24 in FIGURE 3, re-
frigerant flows from the indoor coil 11, which then oper-
ates as the condenser, through line 20 and through
capillary tube 17. Under such conditions, the flow of
refrigerant through line 19 is blocked by check valve 21.

A conventional drier 24a may be interposed in the
line leading to the capillary tubes to withdraw any mois-
ture from the refrigerant charge. To avoid chemical
breakdown of the refrigerant, it is desirable to maintain
the moisture level below forty parts water per one million
parts refrigerant.

All of the parts of the closed system so far described
are entirely conventional. Since such components, in-
cluding the drier 25, capillary tubes 17 and 18, compres-
sor 12, reversing valve 13, and coils 10 and 11, are well
known components of heat pumps, a further description
of their structure is believed unnecessary herein.

Adjacent coil 11, which operates as a condenser when
the smaller refrigerant charge is required, is a storage
tank 25. The refrigerant storage tank is completely
sealed except for a single line 26 which enters the bottom
of the tank and which communicates with refrigerant line
20 between coil 11 and check valve 22. It is important
that the storage tank 25 be adjacent to, but spaced from,
coil 11. If the tank is mechanically or physically con-

nected to the coil, then the tank walls would tend to assume the same temperature as the coil itself, resulting in improper operation of the system. Heat transfer between the storage tank and the adjacent coil 11 must be avoided; however, the tank should be positioned close enough to the coil so that its walls will react to the temperature of the air either entering or leaving the coil 11.

Interposed along suction line 15 is a vertically-elongated accumulator tank 27. Portion 15a of line 15 communicates with an opening at the upper end of the accumulator tank and serves as the inlet line therefor. Portion 15b, which extends to the compressor 12, also communicates with a second opening at the upper end of accumulator tank 27 and serves as a discharge line for that tank.

The volume of the accumulator tank is critical. Its capacity must not exceed the volume of oil which the compressor 12 might lose before reaching its lowest operating oil level. In other words, the volume of the accumulator tank must be less than the difference between the maximum and minimum operating oil capacities of the compressor. In practice, it has been found that the accumulator tank capacity should be substantially less than this difference because, in normal operation of the compressor, some oil necessarily circulates through the refrigerant system.

The capacities of the storage tank 25 and accumulator tank 27 are closely related. Specifically, the combined capacities of the storage and accumulator tanks should equal the volume of excess charge which must be removed from the refrigerant system during one of its cycles of operation. Normally, as previously indicated, excess charge must be removed during the heating cycle; therefore, the combined capacities of the accumulator and storage tanks should equal the excess charge which must be removed from circulation through the system in order to achieve the optimum charge when the apparatus is operating at the lowest ambient (outside) temperature to which the outdoor coil is expected to be subjected.

Broken line 28 indicates the physical disposition of the various components when the heat pump is installed for operation. All of the components disposed to the left of line 28 are normally positioned outside of an inclosure and are subjected to outdoor temperatures, whereas those components to the right of line 28 are normally located within an inclosure and are subjected to indoor temperatures.

FIGURES 1 and 2 illustrate the heat pump during a cooling cycle when it operates as an air conditioner. Coil 11 serves as an evaporator, withdrawing heat from the room air space. The vaporized refrigerant is drawn through suction 15 into compressor 12 and is then pumped under pressure to the outdoor coil 11 which serves as a condenser. Storage tank 25 remains empty, since the temperature of its walls remain well above the condensation temperature of the refrigerant and any refrigerant flowing therein through line 26 would quickly boil off. Refrigerant flows into and out of accumulator 27 on its way to compressor 12.

FIGURE 2 illustrates the condition which results during a cooling cycle when the gas returning from the evaporator to the compressor is superheated. Oil, flowing along with the superheated gas, collects in the accumulator. Once the system shuts off or catches up with the load, the oil in the accumulator tank will boil off with liquid refrigerant and return to the compressor. As previously indicated, the capacity of the accumulator must be limited to the volume of oil that can be removed from the system without impairing operation of the compressor.

During a heating cycle (FIGURES 3 and 4) the indoor coil 11 operates as a condenser and the outdoor coil 10 operates as an evaporator. The flow of refrigerant through the circuit is reversed and, since the storage tank 25 taps into the circuit adjacent the condenser, it

collects liquid refrigerant flowing from the condenser. In effect, the storage tank removes from the system that portion of the refrigerant charge which is in excess of the optimum charge required for operation of the heat pump under moderate outdoor temperature conditions. Gaseous refrigerant flows from the evaporator through reversing valve 13 and suction line 15 into compressor 12. Since the returning refrigerant is in a gaseous state during such moderate outdoor temperature conditions, it simply flows into and out of the accumulator tank on its way to the compressor.

As the outdoor temperature drops, coil 10, which acts as an evaporator on the heating cycle, receives decreasing amounts of heat from the air. Under extremely low outdoor temperature conditions, the amount of heat available to the outdoor coil is insufficient to vaporize all the refrigerant and liquid refrigerant therefore flows from the outdoor coil towards compressor 12. However, under such conditions, the accumulator tank 27 operates as an auxiliary storage tank to collect liquid refrigerant and thereby further reduce the charge of refrigerant in the system (FIGURE 4). Liquid refrigerant which might otherwise pass into the compressor to dilute the oil to the point where its lubricating effectiveness is destroyed is thereby avoided. The storage tank 25 and accumulator tank 27 thereby coact to withdraw excess charge from the system during the lowest outdoor temperatures at which the heat pump is expected to operate. The combined capacities of the storage tank and accumulator are such that at very low outdoor temperatures, when flooding of the evaporator coil occurs, there is not enough refrigerant left in the system to dilute the viscosity of the oil enough to damage the compressor.

It will be observed that storage tank 25 is disposed in the air stream of the coil 11 with which it communicates. It has been found that if the storage tank is instead placed in the air stream of the other coil 10 (while retaining its flow of communication with coil 11) serious oil washout may occur and may cause compressor failure, under certain operating conditions. This problem is avoided by locating storage tank 25 adjacent the coil with which it communicates; that is, the coil which operates as a condenser when the smaller refrigerant charge is required.

If the storage tank were instead located adjacent the outdoor coil, while retaining its flow of communication with the indoor coil, and the system were accidentally adjusted into a heating cycle during high summer temperatures, then the storage tank would be filled and the indoor coil would act as a condenser. If the cycle were then reversed, either accidentally or intentionally, the storage tank, which would be exposed to hot outdoor conditions, would empty rapidly, far more rapidly than if it were located as shown adjacent the indoor coil. Liquid refrigerant discharged from the rapidly-emptying storage tank would flow through the outdoor coil and surge into the compressor, causing oil washout and, possibly, compressor failure.

This problem is avoided by locating the storage tank adjacent the coil to which it is connected. Should the same conditions of operation described above accidentally or intentionally take place, the storage tank will empty more slowly and, even if a slug of liquid refrigerant should pass from the evaporator coil towards the compressor, it will be collected in accumulator 27. Relatively slow emptying and filling of the storage tank 25, which results from the location of that tank adjacent coil 11, also has the further advantage of reducing the operating noise level of the system as a whole.

Should the system be such that a larger charge is required during the heating cycle, it is to be understood that the storage tank 25 should again be located adjacent to, and in communication with, the coil which operates as a condenser when the smaller charge is needed; in that case, coil 10. In other respects, the structure and operation would be identical to that already described.

The combined capacities of storage tank 25 and accumulator tank 27 would be equal to the excess charge which must be removed from the system when the indoor temperature is at its lowest practical or expected level.

While in the foregoing I have disclosed an embodiment of the invention in considerable detail for purposes of illustration, it will be understood by those skilled in the art that many of these details may be varied without departing from the spirit and scope of the invention.

I claim:

1. A reversible heat pump circuit comprising a first heat exchanger capable of operating selectively as a condenser or as an evaporator; a second heat exchanger capable of operating selectively as an evaporator; a second heat exchanger capable of operating selectively as an evaporator or as a condenser; a flow resistor connecting said first and second heat exchanger for the reversible flow of refrigerant therethrough, a compressor interposed between said exchangers and completing the circuit, reversing means in said circuit for selectively reversing the direction of flow from said compressor to and from said heat exchangers, the thermal characteristics of the circuit being such that one of the directions requires for efficient operation an effective charge larger than the charge for the other of said directions, a quantity of refrigerant in the circuit corresponding with the larger charge, a refrigerant storage tank equipped with a two-way flow connector which communicates with the circuit between said exchangers and adjacent to the exchanger which operates as a condenser when the smaller charge is needed, and an accumulator tank communicating with the circuits at a point along the compressor's refrigerant intake line, the capacity of said accumulator tank being no greater than the volume of oil which may be withdrawn from the compressor without impairing compressor operation, and the combined capacities of said accumulator and storage tanks being equal to the volume of excess charge present when the flow of refrigerant in said circuit is in said other direction so that a smaller refrigerant charge is needed, and the heat exchanger which then operates as an evaporator is subjected to its lowest expected ambient temperatures.

2. The structure of claim 1 in which said storage tank is disposed adjacent the heat exchanger which operates as a condenser when the smaller refrigerant charge is needed.

3. The structure of claim 1 in which said accumulator tank has inlet and outlet openings communicating with said circuit; said accumulator tank being vertically

elongated and said openings being located adjacent to the upper end thereof.

4. A reversible heat pump circuit comprising a first heat exchanger capable of operating selectively as a condenser or as an evaporator, a second heat exchanger capable of operating selectively as an evaporator or as a condenser; a flow restrictor connecting said first and second heat exchangers for the reversible flow of refrigerant therethrough; a compressor interposed between said exchangers and completing the circuit; reversing means in said circuit for selectively reversing the direction of flow from said compressor to and from said heat exchangers; the thermal characteristics of the circuit being such that a larger charge is required during a cooling cycle when said first exchanger operates as a condenser and said second exchanger operates as an evaporator, and a smaller charge is required during a heating cycle when said first exchanger operates as an evaporator and said second exchanger operates as a condenser; a quantity of refrigerant in the circuit corresponding with the larger charge; a refrigerant storage tank equipped with a two-way flow connector which communicates with the circuit adjacent said second heat exchanger; and an accumulator tank communicating with the circuit at a point along the compressor's refrigerant intake line; the capacity of said accumulator tank being no greater than the volume of oil which may be withdrawn from the compressor without impairing compressor operation; and the combined capacities of said accumulator and storage tanks being equal to the volume of the excess charge present during a heating cycle when said first heat exchanger is subjected to its lowest expected ambient temperatures.

5. The structure of claim 4 in which said storage tank is spaced closely to said second heat exchanger.

6. The structure of claim 4 in which said accumulator tank has inlet and outlet openings located adjacent the upper end thereof.
